UNITED STATES PATENT OFFICE.

TUNIS VANDERWEEEL, OF YONKERS, NEW YORK.

SPINDLE-DRIVING DEVICE FOR SPINNING-MACHINES.

SPECIFICATION forming part of Letters Patent No. 411,842, dated October 1, 1889.

Application filed June 4, 1889. Serial No. 313,083. (No model.)

To all whom it may concern:

Be it known that I, TUNIS VANDERWEEEL, a citizen of the United States, residing in the city of Yonkers, in the county of Westchester, 5 in the State of New York, have invented certain new and useful Improvements in Spindle-Driving Devices for Spinning-Machines, of which the following is a description in such full, clear, concise, and exact terms as will enable any one skilled in the art to which my invention appertains or with which it is most nearly connected to make and use the same, reference being had to the annexed drawings, making a part of this specification, and to 10 the letters of reference marked thereon.

Similar letters of reference indicate corresponding parts in all the figures of drawings.

My invention consists of a novel tension-regulator for the bands employed for driving 20 spindles in ordinary spinning or twisting machines, or machines where power is transmitted from a drum to a small revolving shaft; and it consists of certain novel parts and combinations of parts constituting an 25 improved apparatus for this purpose.

Referring to the accompanying drawings, Figure 1 illustrates a plan view of the driving-band, cylinder, and spindles of a spinning-machine with my improved tension-regulator applied thereto, the spindles being 30 shown in part. Fig. 2 illustrates a front elevation of the same. Fig. 3 is a detail view of the tension-regulator detached from the machine.

The following is a description of the devices 35 illustrated in the accompanying drawings, which show, among other things, my improved regulator in the form in which I now prefer to embody my invention. It will, however, 40 be understood that my invention is not limited to the precise devices shown, as various modifications may obviously be made and parts may be omitted without departing from the spirit of my invention or the scope of the 45 claims concluding this specification, in which the novel and distinguishing features of my invention will be separately and particularly designated.

Referring to Fig. 1, A is a frame or box attached to the machine. Within said box is 50 a cylinder or drum B, extending the entire

length of the machine and connected with any suitable source of power.

D D are whirls attached to the spindle-shafts M M, of any suitable construction. 55

C is a driving-band, by means of which the motion of the cylinder B is transmitted to the spindle-shafts M M, to operate the same.

Instead of each whirl being provided with a separate and independent driving-band, as 60 is common in spinning-machines, I prefer to employ one band to drive several whirls by passing it backward and forward over the drum and around the whirls, substantially as shown in the drawings. I have here shown 65 ten whirls driven by a single continuous band, and I have found by experience that with the tension devices hereinafter described at least that number of whirls may be conveniently driven by one continuous band. 70

As is now well understood in the arts, atmospheric changes cause the driving-bands to shrink and expand, and it is therefore highly desirable to provide the machine with some means of compensating for these 75 changes, so that the tension of the driving-band may be kept constant. Such a device is illustrated in the drawings, and constitutes the subject-matter of my present invention.

Referring to Fig. 1, it will be seen that the 80 driving-band, after leaving the last pulley on each end of the series of the whirls which it drives, is made to pass over an idler-pulley J, which idler-pulley is attached to a tension-arm I, connected with the coiled spring H, 85 supported on the bracket G, attached to the frame of the machine. This device in detail is illustrated in Fig. 3 of the drawings. The bracket G is provided with a slot K and bolt K', by means of which it may be bolted to 90 the frame of the machine and its position varied and adjusted forward or backward to bring its forward end in the desired position. On the forward end of this bracket is attached a coiled spring H, terminating in the 95 tension-arm I, said coiled spring being attached to the bracket by means of a bolt N, preferably provided with a screw-threaded end, to which a nut N' is attached to clamp the parts together and hold the spring in the 100 required position. The tension-arm I carries an idler-pulley J, carried by a hub attached

to a sleeve J', passing over the tension-arm I, which sleeve is provided with a set-screw L, by means of which the position of the idler on the tension-arm may be varied. The pulley J is arranged between the upper and lower bands passing from the driving-drum to the several whirls. Attached to this same bracket G is another similar coiled spring, tension-arm, and idler-pulley to regulate the tension 10 of the driving-band on another series of whirls, substantially in the manner herein described. These springs are separated by the toe of the bracket G, as shown in Fig. 2.

It will be observed that the idler-pulley is 15 placed between the upper and lower bands passing from the driving-drum to the several whirls. In this position it is able to take up the slack of the band without tending to draw it off the end whirls and without subjecting 20 said whirls to unusual strain, thus avoiding the necessity for additional idler-pulleys to guide the band, which are for many reasons objectionable. By this arrangement the banding 25 of the machine may be changed to reverse the operation of the spindles without inconvenience and without changing the adjustment of the parts.

The most common method of transmitting the motion of the cylinder B to the several whirls 30 of the machine is, I have hereinbefore pointed out, by separate driving-bands, which whirls being provided by an independent band passing around the cylinder and around the whirl. This means of driving the whirls is 35 exceedingly objectionable, because the bands have to be made tight to prevent slipping, and a slight change in the length of the band, due to stretching by use and to atmospheric conditions, interferes with the proper spinning 40 of the yarn and results in an uneven and unsatisfactory product. Besides, the strain upon the driving-band in machines of this character is very severe, owing to the fact that the motion of the driving-drum is not 45 uniform, but is stopped and reversed during each complete cycle of motions of the machine. This causes such bands frequently to break, and much time is consumed in repairing them. To overcome these difficulties, long continuous bands, each driving a 50 number of whirls and arranged substantially as shown in the drawings, have been used, and with such bands regulating devices to take up the slack and to maintain a constant 55 and uniform tension upon the bands have been employed; but these devices are all more or less objectionable, because they are expensive, somewhat complicated, and require lubrication. Besides they are apt to be clogged by 60 fragments of yarn and are not readily and properly adjustable to obtain the desired tension on the band.

My improved tension device is free from all 65 these objections. It is very simple in construction and contains no parts which are liable to become clogged by dust or fiber about the machine. It does not require oiling to

keep it in running order. It is exceedingly efficient and furnishes means for ready and satisfactory adjustment.

It will be seen by reference to the drawings that the position of the coiled spring H may be varied and the direction of the tension-arm I adjusted to any desired position. Thus the nut N' may be loosened, the arm I turned 75 to the desired position to obtain the requisite tension on the band, and then held there by tightening the nut N'. The tension upon the driving-bands may also be varied by moving the idler-pulley J toward and away from the 80 spring H. As it approaches the spring H the tension on the band will be increased, and as it moves away from the spring H the tension on the band will be decreased; also, by varying the position of the idler-pulley on the arm 85 I the position of the idler may be determined to suit different machines.

One of the advantages of making the tension device substantially as illustrated in the drawings, in which the tension-arm is made 90 of spring metal and is formed of an elongation of the coiled spring, consists in the great flexibility thus imparted to the device and its ready adaptation to all conditions of use. In many, if not all, of the tension-regulators heretofore made great care has to be exercised in 95 properly attaching the device to the machine and in adjusting it to the required work. In my tension-regulator, however, the parts which support the idler-pulley are so completely supple that the pulley will readily accommodate itself to the bands without necessitating the exercise of any considerable amount of care in placing it on the machine. Besides, the bands which operate the spindles sometimes move in one direction and sometimes in 100 another during the operation of twisting, backing, and winding the yarn, and these changes of direction are made suddenly. If 105 the idler-pulley be unable to move readily in any given direction, the liability of wearing and breaking the bands and of running the bands off said pulley or off the whirls is very great. In the structure above described, however, it will be observed that the spring-support 110 of the idler-pulley permits it to move in any direction without undue strain upon the band, while it gives a constant and even tension upon the band. The coiled spring H permits it to move forward and backward. The 115 elasticity of the arm I permits it to move up and down, and the twisting or torsion of the arm I insures the pulley standing always in exactly the line of the band passing around it without requiring very careful adjustment to 120 attain this end. The sleeve to which the pulley is attached may not only be moved longitudinally on the arm I, but it may also be turned to secure the desired inclination of 125 the pulley and firmly held in position by the set-screw L. This adjustment is a matter of considerable importance, because it is desirable to have only enough tension on the driving-bands to prevent slipping, and any unnec-

essary increase of tension diminishes the life of the bands materially under the strain to which they are put in stopping and reversing the whirls. Again, by having the idler-pulley adjustably attached to the tension-arm, if more or less than ten whirls are arranged in series driven by a single band, the idler may be readily moved to a central position without changing the position of the supporting bracket.

Having thus described my invention, what I claim, and desire to secure by Letters Patent, is—

1. In spindle-driving devices for spinning-machines, the combination of a spindle, a driving-drum, a driving-band, a tension-arm made of spring metal coiled at one end to form a spring and having its other end free, and a sleeve to which said pulley is attached longitudinally adjustable on said arm, substantially as described.

2. In spindle-driving devices for spinning-machines, the combination of a series of spindles, a driving-drum, a driving-band passing alternately about the drum and the spindles and from one end spindle to the other end spindle, a bracket, a spring, a tension-arm controlled by said spring, an idler-pulley, and a sleeve to which said pulley is attached longitudinally adjustable on said arm, said pulley being arranged between the bands passing

over and under said driving-drum to the whirls and acting on the band between the end spindles, substantially as described.

3. In a tension-regulator for spindle-driving bands, the combination of a spindle, a driving-drum, a driving-band, a spring, a tension-arm controlled by said spring, a bracket to which said spring is attached, and a set-screw for securing said spring to said bracket and for adjusting the tension of said spring, substantially as described.

4. In spindle-driving devices for spinning-machines, the combination of a series of spindles, a driving-drum, a driving-band passing alternately about the drum and the spindles and from one end spindle to the other end spindle, a bracket, a spring, a tension-arm controlled by said spring, an idler-pulley, a sleeve to which said pulley is attached longitudinally adjustable on said arm, said tension-arm being made of spring metal and having a free end adapted to move up and down as well as forward and back, and said pulley being arranged between the bands passing over and under said driving-drum to the whirls and acting on the band between the end spindles, substantially as described.

TUNIS VANDERWEEEL.
